United States Patent Office

Des. 212,104

Patented Aug. 27, 1968

212,104

EXERCISING DEVICE

Alexander G. McDonald, West Covina, Calif., assignor
to Buddy Systems, Inc., Covina, Calif., a corporation
of California

Filed Oct. 31, 1967, Ser. No. 9,227

Term of patent 14 years

(Cl. D34—5)

FIG. 1.

FIG. 2.

FIG. 3.

FIG. 4.

FIG. 5.

FIG. 1 is an isometric view of an exercising device embodying my new design;

FIG. 2 is a front elevational view thereof;

FIG. 3 is a side elevational view thereof;

FIG. 4 is a top plan view thereof; and

FIG. 5 is a bottom plan view thereof.

The rear elevational view of the exercising device shown is the same as the front elevational view illustrated. The side elevational view not shown of the exercising device is the same as the one side elevational view illustrated.

I claim:

The ornamental design for an exercising device, substantially as shown and described.
